(57) **CLAIM**

The ornamental design for a section as shown and described.

DESCRIPTION

DESCRIPTION OF THE FIGURES

FIG. 1 is an upper end perspective view of a section from a first side thereof;

FIG. 2 is an upper end perspective view of the section shown in FIG. 1 from a second side thereof;

FIG. 3 is a lower end perspective view of the section shown in FIG. 1 from the second side;

FIG. 4 is a lower end perspective view of the section shown in FIG. 1 from the first side;

FIG. 5 an elevation view of the end of the section shown in FIG. 1;

FIG. 6 is an upper end perspective view of a second embodiment of a section from a first side thereof;

FIG. 7 is an upper end perspective view of the section shown in FIG. 6 from a second side thereof;

FIG. 8 is a lower end perspective view of the section shown in FIG. 6 from the second side;

FIG. 9 is a lower end perspective view of the section shown in FIG. 6 from the first side; and

FIG. 10 an elevation view of the end of the section shown in FIG. 6.

The section is shown with a symbolic break lines. The appearance of any portion of the section between the break lines forms no part of the claimed design.
